UNITED STATES PATENT OFFICE.

DONALD H. WEST, OF NEW LONDON, CONNECTICUT, ASSIGNOR TO THE J. N. LAPOINTE COMPANY, OF NEW LONDON, CONNECTICUT, A CORPORATION OF MAINE.

HYDRAULIC DRIVE FOR BROACHING MACHINES AND THE LIKE.

Application filed March 26, 1924. Serial No. 702,054.

This invention relates to improvements in a hydraulic drive for broaching machines and the like. More particularly it relates to machine tools wherein there is a reciprocating member; whose stroke in one direction is a working stroke executed under high pressure and necessarily at relatively slow speed, but whose return stroke is without load or practically so. In such cases it is desirable to provide a relatively quicker return stroke. It is the object of the present invention to accomplish this without certain sacrifices and objectionable features which have attended previous efforts in this direction.

The hydraulic drive for such apparatus may be operated by a pump, and various devices are known for changing the flow of oil or other liquid, as to direction and rate, but it is most convenient to have a pump which can ordinarily be driven always in one direction and at constant speed. The invention may be applied with such a pump, as well as with variable speed and variable output pumps. The reciprocating member is ordinarily a piston driven to and fro in a cylinder. Assuming that the driving pump, when operating at full speed, can deliver a certain maximum volume of oil per minute, and a greater speed of return stroke is desired, this can be obtained by designing the piston and cylinder of smaller diameter, because the cylinder will then become filled more quickly. But with the smaller piston area the intensity of pressure on the working stroke has to be higher which is detrimental both on account of the heavier construction required to resist the stresses, and because of the compressibility and increased elastic effect of the oil which is ordinarily used as the working medium. Another alternative would be to employ a pump of considerably greater capacity, and to run it at reduced output on the working stroke; but this is costly for size of pump and for cost of applying it to a machine of this kind, as well as less efficient. It is an object of the invention to provide for obtaining a return stroke of much greater speed than the working stroke without the objectionable incidents above mentioned, and to do this with an arrangement which is economical of space as well as simple in construction.

These objects are attained by arranging a combination of cylinders, one of suitably

large size for the working stroke and another of suitably small size for a quick return stroke, the latter, in the preferred form, being housed within the former. To this end, the piston rod, which transmits power from the working piston to the reciprocating element, as for example to the draw rod and tool in a broaching machine, is made tubular and hollow to near the tool; and its hollow is extended through the working piston. Thus it becomes an open-ended small cylinder, moving to and fro with the piston and tool-head; and a fixed tube is inserted into this hollow from the head or drive end of the machine so as to telescope into it with a smooth running fit, when the working piston moves to and fro. The end of this piston rod which is toward the tool is of course closed. Piping connections are provided by which the pump on the working stroke delivers oil into the large cylinder against the working piston, and on the return stroke delivers oil into the smaller cylinder, against the tool head end of the small cylinder. As the working cylinder is much the larger, in volume to be filled per foot of travel, the delivery of any certain volume from the pump will move the piston and tool head considerably farther in a given time if it be put into the small cylinder than if put into the large cylinder. Therefore, if the pump discharge be directed into each in turn, at its fixed normal or maximum capacity, it will return the tool head much more rapidly than it draws it on the working stroke.

To this end the pump is in effect compounded with the working piston which it drives to displace oil in the working cylinder at a rate much greater than the pump alone would displace it; but all of the work stroke is through the pump alone.

In each case relief is provided for the flow of oil, other than that which goes through the pump, so as to make the parts all free moving. In particular, such a conduit is arranged leading from the high pressure side of the working piston to its pressure-free side, for the return stroke. For preparation for the working stroke a suitable valve may close this passage simultaneously with the reversal of pump or pump connections; and the same valve may simultaneously open another passage for the flow of oil freely out from the said pressure-free side of the working piston to the pump, to be

delivered thereby under high pressure directly into the working cylinder on the high pressure side of the piston. An elevated reservoir for oil open to atmosphere, connects with the main cylinder on its pressure-free side, and on its pressure side at stroke-ends if desired, to receive and to supply the differential of oil for keeping the system filled at all positions of the main piston, and to free the oil itself from air which gets into it. All of this part is automatic, and results from the application of the pump discharge against the working piston on the working stroke and against the tool head (in effect) on the return stroke.

The invention may be embodied in various arrangements of parts, passages and connections for attaining the same general result, that which has been described above being a preferred form. Its application is not limited to horizontal cylinders, nor to broaching machines, but it is applicable generally to hydraulic systems for propelling a reciprocating element powerfully and slowly in one direction, as on a working stroke, and rapidly in the other direction, as on an idle return stroke.

It is intended that the patent shall cover by suitable expression in the appended claims, whatever features of patentable novelty exist in the invention disclosed.

In the accompanying drawing:

Figure 1 is an elevation representing in diagram and in section, a preferred form of embodiment of the invention; with the parts arranged and arrows showing flow as on the return stroke; and

Figure 2 is a similar view of a detail of Figure 1, the slide valve; but this is shown in the closed position which occurs between strokes.

The drawing indicates the frame 10 of a horizontal broaching machine of the pull broach type wherein a tool holding head 12 is moved to and fro by a draw rod 14. The latter is moved on its working stroke by the piston 18 fast on its end within the main cylinder 16. In the preferred form of the invention this draw rod is tubular having one end open through the piston, but having its end which is toward the tool head 12 closed. Any suitable liquid, customarily oil, is propelled by a pump 20 of any suitable type in such manner that the oil is alternately forced into the expandible chamber 19 on the near side of the piston between the draw rod 14 and the walls of cylinder 16 (which space will be herein for convenience called the "work chamber") thus driving the piston 18 on the working stroke, and into the expandible chamber 21 within the draw rod (herein referred to as the "return chamber"); the oil being in each case simultaneously withdrawn from the other chamber. This involves a reversal of flow of the liquid, which

may be effected either by a reversal of the direction of discharge of the pump or by other suitable means. The pump 20 is indicated diagrammatically as being a variable displacement piston pump continuously rotating in the same direction, in which the pistons are eccentric, flow ceasing when they are set into concentric relation, where they have a stroke of zero length, and beginning in the opposite direction when they are set past the center into eccentricity on the other side. Such pumps driven by electric motors are well known and therefore the details are not illustrated.

In the preferred form of the invention the idle chamber 23 on the remote side of the piston 18 is filled with oil with constantly open connection to an elevated open reservoir 24 of oil; except that a stationary pipe 22 extends axially through the remote head of the main cylinder 16 so as to telescope within the draw rod 14 with an easy running fit. This should fit tightly enough, aided by packing if needed, so that there is little or no escape of oil past it from the interior of the draw rod. This fixed tube 22 delivers into the return chamber 21 being connected by a pipe 26 with the low pressure discharge pipe 25 of the pump 20. The relief valve 27 provided for this part of the system may be set so as to open at a low pressure, slightly exceeding that which is required to drive the rod and tool head idly back on their return stroke. For example, in one machine embodying the invention wherein the chamber 21 within the draw rod has a diameter of two and one-eighth inches a setting of this relief valve to open at 200 pounds was found suitable to give protection in case unusual resistance should be encountered. This relief valve may conveniently discharge into a reservoir 30 shown in the drawing as underlying the apparatus and receiving also a drain 29 from the pump for any oil that may leak out therefrom, and one from the relief valve 37 of the high pressure pipe 36 leading from the pump 20 to the work chamber 19. The relief valve 37 for this part of the system must be set to operate at a very high pressure, in a machine of the character described, for example at 2000 pounds per square inch, because of the high resistance encountered by the tool which is drawn on its working stroke by the piston 18 when oil is forced into the working chamber 19. A pipe 46 provides a by-pass around the piston between the ends of the main cylinder 16, that is, between the work chamber 19 and the idle chamber 23, and is provided with a valve, which may conveniently be a slide valve 47 operated by rod 48, for opening and closing such by-pass. This valve 47 may also control a connection between the low pressure discharge 25 from the pump and the idle chamber 23 of the main cylinder, by controlling an

inlet from the pipe 26 to the said by-pass 46 in such manner that when the pump is set to propel oil outward through the low pressure pipe its discharge enters only the pipe 26, and through it the return chamber 21; but when the pump is set to fill the work chamber 19 this valve 47 is set so that oil comes to the pump both from pipes 26 and 46 and thus comes from both the return chamber 21 and the idle chamber 23. Such shifts are effected in pumps of this character by a movement of one or the other elements in the pump; and in the present case this is accomplished by the control rod 50 which is actuated either by hand as through the lever 52, or automatically as by the engagement of a lug 54 on the tool head with a lug 53 associated with the hand lever 52 and rod 50, to stop the motion in the returning direction, or by its engagement with a similar lug 55 to stop its working stroke. These arrangements may be varied as desired according to any known or suitable style, but it is convenient for the purpose of the invention that the pump control rod 50, however actuated, be connected also to the valve rod 48 so that simultaneously with the shifting of the pump there is a shifting of the valve 47. The slide valve 47 should be so connected that when the pump comes to zero output the connection from pipe 46 to the work chamber 19 becomes closed; and so that when the output of the pump begins and increases in the opposite direction that part of the valve which closes the connection from 46 to 26 opens simultaneously with the beginning and increase of pumping in said opposite direction. Under these circumstances the invention permits the electric motor or other drive of the pump to run always at full speed, and permits the delivery of the pump to be always at its maximum capacity, except while being shifted from one direction to the other or while stopped. The pump may therefore be designed to have such output as is necessary in order to produce the desired maximum speed of the working stroke, that is, for expanding the work chamber 19 at a pressure say of 2000 pounds. A gage 19' may be provided for showing pressure conditions within the work chamber, by which the resistance of the work to the stroke may be observed, enabling the operator to reduce the rate of the pump if the load is extreme, or to tell how much he can increase its rate on lighter work, if the pump happens to be operating at less than maximum output. According to the nature of the work which is to be done the regular speed for a particular job may be fixed either at the maximum capacity of the pump or something less if it be desired to operate through the work more slowly, which last might be either for the sake of the work or for getting greater pressure from a given motor of small size.

66 The operation of the apparatus thus de-

scribed is extremely simple. Assuming that the apparatus is designed for the reversal to occur by a reversal of direction of the delivery of pump, for the working stroke the pump takes oil from the return chamber 21 and the idle chamber 23 and forces it into work chamber 19. Then oil thus crowded out of idle chamber 23 by the advancing piston 18 is more than can be received in the work chamber 19, because the rod 14 is larger than the tube 22 which telescopes within it; and enough oil to compensate for this is crowded up into the reservoir 24. When the stroke is ended the shifting of rod 48, either automatically or by hand, simultaneously with the shifting of the pump, stops all motion. When the return stroke is to begin the further shifting of rod 48 causes oil to be taken from the work chamber 19 and to be forced by the pump through the pipe 26 into the return chamber 21, filling that chamber very rapidly because it is so small, and thus returning the tool head, draw rod and piston 18 to position for another working stroke very quickly, as compared with the time taken for driving them on the working stroke, while the excess of oil forced from the work chamber 19 by the advancing piston 18 flows through the by-passage 46 into the idle chamber 23; and some oil is drawn into the idle chamber 23 or from the reservoir 24, to compensate for the thickness of the walls of the draw rod 21.

It is not necessary that the idle chamber 23 contain oil. But it is advantageous to have oil in the chamber 23 because it reduces the likelihood of air getting past the piston 18 into the working body of oil and rendering it more elastic, and because it makes it less important to have a tight packing between the fixed rod 22 and the sliding rod 21 which telescopes over it. Any small leakage of oil which then may occur will not materially slacken the speed of the return idle stroke nor introduce any problem of disposal of the leakage.

110 It is desirable that the body of oil should be free from air, the presence of which introduces an element of compressibility and resilience into the fluid medium which in turn reduces the positiveness of operation of the tool and introduces irregularities. The invention provides means, for maintaining the oil free and clear of air, which are valuable in cases where elasticity of the fluid medium is objectionable, by arranging reservoir 24 at the highest part of the system and having a connection thereto from the top level of the idle chamber 23, so that any air bubbles which get into the system and are carried by the oil to this part of it may rise to its top and thence rise to the reservoir 24 and escape. A similar clearance for escape of air is provided on the work chamber end by providing a connection from the work chamber to the reservoir 24 having a valve 54 adapted to be closed 125

by pressure within the work chamber or by flow of oil out from the work chamber into the reservoir and having a weak spring 55 which opens the valve in the absence of controlling circumstances. The spring should be weak enough so that this valve will be thus closed even during the return stroke by the slight pressure or outflow of oil; but it will be opened by the spring at the end of stroke 10 in either direction and remain open while there continues to be neither pressure nor flow. This periodic opening of the work chamber beneath a body of oil permits the rising and escape of any air that may be within 15 and insures its being filled with oil at the beginning of each working stroke:

The casing and valves in the circulating system may be of any suitable kind and are not necessarily operated by a single unit as 20 illustrated in the valve 47. The arrangement shown is, however, especially advantageous for a machine of the character mentioned. In this the barrel of the valve 47 has a longitudinally movable plug bored from the end and from the top. Oil from the work chamber may enter its top when it is properly positioned to open the by-pass; and may at all 25 times pass by this plug, between work chamber and pump, by passing through a chamber 20 47' in the wall of the valve which surrounds this plug.

A circulating pump 60 may be employed to carry oil constantly or at intervals up from the drain pan 30 to the reservoir 24; with an 35 overflow pipe 61 from the latter into the pan 30.

The reservoir 24 is not necessarily elevated to above the cylinder nor the pan 30 set below the relief valves and pump. These may be 40 otherwise arranged.

The return chamber is not necessarily housed within the main cylinder 16 and draw rod 14, although this is most convenient, but the arrangement of the return cylinder on the 45 axis of the work cylinder as illustrated has many advantages.

It will be understood that while the foregoing explanation has been made upon the assumption that the reversal of flow is occasioned by the reversal of direction of output of the pump, the invention is not limited to that particular embodiment of means for reversing the connections of intake and discharge of the pump, while the pump itself 55 operates continuously in one direction at its predetermined full speed; provision being made for idling of the flow while both said connections are closed.

Other variations may be made. The invention 60 has been herein described with reference to a horizontal pull broaching machine. In such machines, which may for example be of the type illustrated in United States Letters Patent 1,073,251, it has long been a problem 65 to provide a powerful positive drive pulling

the tool at suitable speed on the working stroke and returning the tool quickly for the next stroke, the requirements of the two strokes being mechanically contradictory and the mechanism which is adapted for one has hitherto been unsuitable for the best ideals of the other, even when hydraulic drive has been used. The present invention, by its housing of the small return cylinder on the inside of the draw rod, thus by simple mechanism 70 compounding the pump action for the return stroke and providing for its free circulation through the by-passage, with constant elimination of air, provides a drive which renders the action of a broach positive and steady 75 despite variations in the resistance of the work, reduces the momentum of moving parts, and applies to each part of the stroke the type of power it needs. Obviously the 80 invention can be applied with advantage to other types of broaching machines and to machines other than broaching machines so that it will be understood that the fragments of machine frame which are shown in the diagrammatic drawing may serve to represent the frame of any machine to which the 85 apparatus is applied.

I claim as my invention:

1. A hydraulic drive for a reciprocating element, having in combination, a pump, having a predetermined output; a cylinder with piston, constituting an expandible chamber; a rod extending through the chamber, rigidly connecting the piston to the said reciprocating element and arranged to pull said element on the working stroke; and a cylinder of smaller cross section than the net cross section of the said chamber through which said rod extends, said smaller cylinder being arranged to effect the return stroke, whereby for the same predetermined pump output the return is more rapid.

2. The combination, in a hydraulic drive for a reciprocating element, of a pump having a predetermined output and an expandible chamber for effecting a working stroke of the element, with an expandible chamber of smaller cross section for effecting its return stroke, whereby for the same predetermined pump output the return is more rapid; the return chamber being housed within the work chamber.

3. The combination, in a hydraulic drive for a reciprocating element, of a pump having a predetermined output; a cylinder; with piston and rod attached to the reciprocating element for effecting a working stroke of the element; said rod being tubular and opening through the piston; and a stationary space connection for the opening of said reciprocating rod whereby said tubular rod with said space constitutes another and smaller chamber, expandible for effecting the return stroke more rapidly with equal pump output.

4. The combination, in a hydraulic drive for a reciprocating element, of a pump having a predetermined output; a cylinder; with piston and rod attached to the reciprocating element for effecting a working stroke of the element; said rod being tubular and opening through the piston; and a stationary space connection for the interior of said rod whereby said tubular rod with said space constitutes another and smaller chamber, expandible for effecting the return stroke more rapidly with equal pump output; the said space connection being a tube telescoping within the piston rod and connected with the pump.
5. The combination, in a hydraulic drive for a reciprocating element, of a circuit for the reciprocation of the liquid driving medium, comprising a pump; an expandible chamber in the circuit, terminating said circuit on one side of the pump, having a moving end wall for effecting a working stroke of the element; an expandible chamber in and terminating the circuit on the other side of the pump, being of smaller cross section and having a moving end wall for effecting a return stroke of the element; a container having capacity for a part of the medium at atmospheric pressure; connections in said circuit whereby the pump alternately can shift liquid from each chamber to the other chamber; a connection between the said moving walls of the respective chambers whereby, during expansion of the smaller chamber on the return stroke, its moving wall moves to an equal distance the end wall of the larger chamber and thereby displaces liquid contents of the larger chamber at a rate exceeding the simultaneously occurring shifting of liquid from the larger chamber to the smaller chamber by the pump; a connection from the larger chamber to the said container, open during the shifting from the larger chamber and passing into the container the said excess liquid displaced; a connection from said container to the circuit on the same side of the pump on which the smaller chamber is connected, open on the working stroke; and a valve whereby the said connections of container to working chamber and to pump are made alternately.
6. The combination, in a hydraulic drive for a reciprocating element, of a pump, and a cylinder, piston and piston rod, arranged and connected to the pump for effecting the working stroke with a pull through said rod, the hydraulic drive being applied to the piston on the area around the piston rod; and means whereby, for the return stroke, the said hydraulic drive is applied at the axis on an area smaller than the cross section of the rod, whereby said pump is compounded, with the said piston acting as a plunger to displace the contents of said cylinder at a rate greater than the direct pump displacement.
7. The combination, in a hydraulic drive for a reciprocating element, of a pump; a pair of expandible chambers, one of these chambers being larger than the other of them and comprising a cylinder and piston with piston rod providing a pull through the rod for moving said element on its working stroke, and the smaller of these chambers having its moving wall located at a distance from the said piston toward the said element and operating to effect the return stroke of said element; a chamber for idle liquid; and connections whereby the pump is supplied from the return chamber and the idle chamber and delivers to the work chamber on the work stroke; while on the return stroke liquid passes through pump to the return chamber, and by-passes the pump from the work chamber to the idle chamber.
8. The combination, in a hydraulic drive for a reciprocating element, of a cylinder with piston and rod connected to said element; a by-passage from one end of the cylinder to the other having a valve which can be set to open or close the by-passage; a pump; another passage, from said end of the cylinder through the pump and having a fork after passing through the pump, one branch of which has a valve and leads to the said other end of the cylinder; and a second cylinder, for returning the reciprocating element; the second of said branches leading to the said second cylinder.
9. The combination, in a hydraulic drive for a reciprocating element, of a main cylinder with piston and piston rod attached to the element, the space on one side of said piston comprising a work chamber and on the other side an idle chamber; a return chamber within the piston rod; a pump, means to reverse the direction of its output, and liquid forced thereby alternately into the work chamber and the return chamber; and means for conserving the liquid which is forced out of the work chamber by the piston during the return stroke of the element and for supplying it to the pump to be forced into the working chamber on the working stroke.
10. The combination, in a hydraulic drive for a reciprocating element, of a main cylinder with piston and piston rod attached to the element, the space on one side of said piston comprising a work chamber and on the other side an idle chamber; a return chamber within the piston rod; a pump, means to reverse the direction of its output, and liquid forced thereby alternately into the work chamber and the return chamber; and means associated with the idle chamber for conserving the liquid which is forced out of the work chamber by the piston during the return stroke of the element and for supplying it to the pump to be forced into the working chamber on the working stroke.
11. The combination, in a hydraulic drive for a reciprocating element, of a main cylin-

der with piston and piston rod attached to the element, the space on one side of said piston comprising a work chamber and on the other side an idle chamber; a return chamber within the piston rod; a pump connected by conduits with said chambers; means to reverse the direction of output of the pump, and of liquid forced thereby alternately into the work chamber and the return chamber; a reservoir open to atmosphere associated with the idle chamber for conserving the liquid which is forced out of the idle chamber by the piston during the working stroke of the element, and which is in excess of the capacity of the work chamber to receive, and for supplying it to the pump as a part of the liquid to be forced into the working chamber on the working stroke of the element.

12. Hydraulic driving means for a reciprocating element comprising a main cylinder with piston and rod connection to said element, the cylinder being at one end a work chamber and at the other an idle chamber; a by-passage from one end of the cylinder to the other having a valve which can be set to open or close the by-passage; a return chamber arranged within the piston rod, opening through the piston; a compensating reservoir connected with the idle chamber; a pump; connections between the chambers and the pump; and a working liquid moved by the pump through said connections.

13. A hydraulic drive for a reciprocating element comprising the combination of a work cylinder and piston; connections whereby the expansion stroke of the piston in the cylinder is a pulling stroke; a smaller other cylinder for the return stroke, connected to receive on the return stroke liquid displaced from the work cylinder on the same stroke; a liquid pump; an idle chamber to receive liquid forced from the work chamber on the return stroke; and connections to supply said liquid from both the said smaller chamber and the idle chamber to the pump and thence to the work cylinder on the work stroke; said idle chamber being in the main cylinder on the side of the piston remote from the work chamber.

14. A hydraulic drive for a reciprocating element comprising a cylinder with piston, the piston rod side of which cylinder comprises a working chamber; a return chamber housed within the piston rod; a telescoping tube affording connection thereto; a by-pass around the piston from one end of the first mentioned cylinder to the other; and a positively controlled valve in the by-pass arranged to be shut for the working stroke and opened for the return stroke.

15. The combination, with a hydraulic drive system for a reciprocating element, of a large expansible chamber open to receive flow from one direction for a slow work

stroke; a small expansible chamber open to receive flow from the other direction for a rapid return stroke; a pump, means to reverse direction of its output and liquid forced thereby for effecting the strokes alternately; a high pressure relief valve in the connections between pump and working chamber; a low pressure relief valve in the connections between pump and return chamber; a pan and drains thereto from the relief valves; an idle chamber receiving discharge from the large expansible chamber, and a compensating reservoir connected thereto; and means for interflow of the contents of the drain pan and the reservoir.

16. The combination, with a hydraulic drive system for a reciprocating element, of a working chamber for a work stroke; another chamber for return stroke; a pump, means to reverse the direction of its output, connections from said pump to said chambers, and liquid forced thereby for effecting the strokes alternately; relief valves in the connections to the said chambers; a pan for drain from said relief valves; an idle chamber receiving discharge from the large expansible chamber and a compensating reservoir connected thereto; and a circulating system having a pump delivering liquid from the pan to the reservoir, and an overflow passage from the reservoir to the pan.

17. The combination, in a hydraulic drive for a reciprocating element, of a main cylinder with piston and piston rod attached to the element, the space on one side of said piston comprising a work chamber and on the other side an idle chamber; a return chamber within the piston rod; a pump, means to reverse the direction of its output, and liquid forced thereby alternately into the work chamber and the return chamber; and an elevated reservoir and connection to it from the top of said idle chamber for air relief therefrom.

18. The combination, in a hydraulic drive for a reciprocating element, of a main cylinder with piston and piston rod attached to the element, the space on one side of said piston comprising a work chamber and on the other side an idle chamber; a return chamber within the piston rod; a pump, means to reverse the direction of its output, and liquid forced thereby alternately into the work chamber and the return chamber; and an elevated reservoir having connection with the top of said work chamber through a valve, with weak spring, for air relief from said work chamber.

19. The combination, in a hydraulic drive for a reciprocating element, of an expansible chamber for effecting its working stroke, with an expansible chamber of smaller cross section for effecting its return stroke, whereby, for equal liquid displacement by the source

of power the return is more rapid; the return stroke chamber being housed within the work chamber.

20. A hydraulic drive for a reciprocating element comprising the combination of an annular expansible working chamber; a return chamber co-axially arranged within the working chamber; liquid pressure means having connections with both chambers; and 10 means controlling the application of the liquid pressure to the said chambers selectively.

21. A hydraulic drive for a reciprocating machine element especially adapted for broaching machines comprising two pressure cylinders of different diameters, the larger of them being set for the working stroke and the smaller of them for rapid return stroke; a relief space, open to atmosphere, comprising the space on the side other than the pressure side 20 of the piston of the large cylinder; a pressure pump continuously connected with the pressure chambers of the two cylinders by conduits acting alternately under suction or pressure in accordance with direction of the pump 25 output; a pressure medium, and a valve controlling the flow through said conduits of said medium; means for reversing the direction of medium flowing from the pump; said conduits and valve being arranged so that the 30 valve during the pressure stroke in the small cylinder connects the relief space with the pressure space of the large cylinder, and during the pressure stroke in the large cylinder connects the relief space with the suction side 35 of the pump.

22. A hydraulic drive for a reciprocating

machine element especially adapted for broaching machines comprising two pressure cylinders of different diameters, the larger of them being set for the working stroke and 40 the smaller of them for rapid return stroke; a relief space open to atmosphere; a pressure pump connected by conduits with said cylinders; a pressure medium and a valve controlling flow of said medium through said conduits; means for reversing the direction of flow of said medium from said pump; the whole being arranged with the pump, conduits and valve providing the cylinders alternately with pressure medium; and said 50 conduits being so arranged that on the working stroke the pump draws from the small cylinder and the relief chamber, and discharges into the large cylinder; but on the rapid return stroke some of the pressure medium can pass directly from the large cylinder to the relief chamber without having to 55 pass through the pump while other of it passes from the large cylinder through the pumps of the small cylinder; and an open 60 reservoir having a connection at the highest point of the oil enclosure in the pressure chamber of the large cylinder, and a non-return valve closing by movement in outward direction from the pressure chamber when the 65 oil therein is under pressure, and self opening when the oil therein is not under pressure, providing for automatic air relief.

Signed at New London, Connecticut, this twentieth day of March, 1924.

DONALD H. WEST.
